UNITED STATES PATENT OFFICE.

HENRY E. HUBBELL, OF NEW YORK, N. Y.

SANITARY MASK.

Substitute for application Serial No. 327,642, filed October 1, 1919. This application filed October 12, 1923, Serial No. 668,052. Renewed August 12, 1925.

To all whom it may concern:

Be it known that I, HENRY E. HUBBELL, a citizen of the United States, residing at Bronx, New York city, in the county of Bronx and State of New York, have invented new and useful Improvements in a Sanitary Mask, of which the following is a specification.

This application is a substitute of application 327,642 filed October 1, 1919.

My invention relates to new and useful improvements in sanitary masks, and has for its object to provide an exceedingly simple and effective device of this character for use by doctors, nurses, attendants for sick persons or others in which the plegget or pad is readily and easily removed and attached so that a new pad may be substituted for the used one.

Another object of the invention is to provide in a mask a flexible holder of celluloid, thin metal or other suitable similar material so that when placed upon the face it will approximately conform to the contour of the face in the region or locality of the nose and mouth.

A further object of the invention is to provide attaching means for the mask which may be readily and quickly attached and detached to permit the substitution of new ones.

With these ends in view, this invention consists in the details of construction and combination of elements hereinafter set forth and then specifically designated by the claims.

In order that those skilled in the art to which this invention appertains, may understand how to make and use the same, I will describe its construction in detail, referring by numerals to the accompanying drawing forming a part of this application, in which:—

Fig. 1, is a front elevation of my improved sanitary mask.

Fig. 2, is a section at the line 2—2 of Fig. 1.

Fig. 3, is a section at the line 3—3 of Fig. 1.

In carrying out my invention as here embodied, 2 represents a holder of relatively thin, flexible, celluloid or similar material which may be sterilized or cleaned when desired and this holder may be of any suitable contour or configuration, but is prefer-

ably wider near the bottom than at the top, while the bottom edge is slightly concaved as at 3 where the mask rests above the chin of the user.

Some distance above the lower edge is formed a mouth opening 4 producing between it and the lower edge, a lower lip bridge 5 while another opening 6 termed the nose opening is cut into the holder from its upper edge thereby forming the nose tabs 7 between said nose opening and the side edges of the holder, and an upper lip bridge 8 between the nose and mouth openings.

In the nose tabs 7 and in the lower portion of the holder are formed tape holes 9. Through the holes 9 in the nose tabs and the holes in the body of the holder are threaded the attaching tapes 10, or other suitable means, which may be passed about the head of the user and the ends thereof tied.

The reference numeral 11 represents the plegget or pad which may be in the form of gauze, absorbent cotton or a combination of the two, or other material if found desirable, and this pad is shaped to approximately correspond to the configuration of the holder so as to cover the mouth and nose openings, and is held in place upon the holder by clasps, clamps or clips 12 such as used for holding a number of sheets of paper together the use of which will be obvious. The pad may be medicated if found desirable or advisable.

In practice the mask is placed upon the face and drawn tightly thereagainst by the attaching means 10 which will cause the nose tabs 7 to engage each side of the nose and the widest part to lie against the cheeks of the user which will properly position the nose and mouth openings to permit breathing, and as the air passes through the pad to the mouth or nostrils the disease germs will collect upon those parts of the pad exposed through the nose and mouth openings, and as soon as the mask is removed from the face of the user the pad may be detached from the holder and thrown away or destroyed and a new one substituted therefor. At the same time the holder may be cleansed or sterilized and the attaching means removed and destroyed or sterilized for further use.

Of course I do not wish to be limited to the exact details of construction as herein shown as these may be varied within the

limits of the appended claims without departing from the spirit of my invention.

Having thus fully described my invention, what I claim as new and useful is:—

- 5 1. As a new article of manufacture, a holder of the class described formed of flexible celluloid having a mouth opening in proximity to its lower end and provided with a nose opening cut into its upper edge,
- 10 separated tabs produced by said nose opening, said tabs having holes in their upper ends, said holder also being provided with holes adjacent its lower edge and attaching tapes threaded through the last named holes
- 15 and the holes in the tabs, as shown for the purpose specified.

2. A mask comprising a flexible holder,

a member consisting of lower and upper lip bridges with the mouth opening therebetween and upwardly projecting spaced nose 20 tabs leaving a nose opening therebetween, said holding member having tape holes therein, and attaching tapes threaded through the last named holes in combination with a pad detachably fastened to the 25 inner face of the holding member and adapted to contact with the face of the wearer, a portion of said pad being forced through the nose opening when the mask is applied.

In testimony whereof, I have hereunto affixed my signature.

HENRY E. HUBBELL.
